UNITED STATES PATENT OFFICE.

PAUL N. WINKLEY, OF CASPER, WYOMING.

AUTOMATIC RELEASING STIRRUP.

1,418,504.

Specification of Letters Patent. Patented June 6, 1922.

Application filed September 28, 1921. Serial No. 503,763.

To all whom it may concern:

Be it known that I, PAUL N. WINKLEY, a citizen of the United States, residing at Casper, in the county of Natrona and State 5 of Wyoming, have invented certain new and useful Improvements in Automatic Releasing Stirrups, of which the following is a specification, reference being had to the accompanying drawings.

10. This invention relates to harness devices, particularly to stirrup mountings for connecting stirrups with saddles such as used by stock men and in fact equestrians of all kinds and has for its object the provision 15 of a novel means for connecting a stirrup with a saddle strap whereby to permit the connection to be automatically released by pressure of the foot in the event that the rider should fall.

20. It is well known that when a horseback rider falls from his saddle or slips therefrom it generally occurs that the boot or foot of the rider catches in the stirrup and causes the rider to be dragged along the 25 ground owing to his inability to extricate his foot from the ordinary stirrup. It is with this fact in view that the present invention has been designed.

An important object is the provision of a 30 stirrup mounting in which the construction is such that the entire stirrup disconnects from the stirrup strap, the parts being ordinarily held in operative engagement by a spring pressed lever which is released by 35 pressure of the foot in the event that the rider falls from the saddle.

An additional object is the provision of a device of this character which will be simple and inexpensive in manufacture, highly 40 efficient in use, positive in action, durable in service and a general improvement in the art.

With the above and other objects and advantages in view, the invention consists in 45 the details of construction to be hereinafter more fully described and claimed, and illustrated in the accompanying drawings in which:

Figure 1 is an elevation of a stirrup provided with a mounting constructed in accordance with my invention, showing the parts in normal or operative position;

Figure 2 is a similar view showing the connection released;

Figure 3 is a detail sectional view through 55 the locking pin and associated parts; and

Figure 4 is an edge elevation of the upper portion of one side of the stirrup.

Referring more particularly to the drawings, the letter A designates a stirrup strap 60 of ordinary construction formed with the usual loop B by means of which the stirrup is attached. In carrying out my invention I provide a stirrup 10 of the usual shape but open at its top. These stirrups are ordinarily U-shaped and in the present instance I have shown the upper end of one arm or side formed with a hinged knuckle 11, while the other end or the end of the other arm is bifurcated to define ears 12 and 13. Formed 65 on one side of this second mentioned arm are downwardly inclined spaced ears 14 which are apertured, as shown. It should be stated that the inner ear 12 at the upper end of the stirrup arm is formed with a hole 15; while 70 the outer ear 13 is formed with a somewhat elongated slot 16.

The numeral 17 designates a bar which is formed at one end with a knuckle 18 pivotally connected with the knuckles 11, and 80 which is formed on the under side of its other end with a recess 19 of a size and shape to accommodate the ear 12. The free end of the bar 17 is formed with a hole 20 designed to register with the hole 15 and the 85 slot 16. The bar 17 is ordinarily disposed through the loop B of the strap A for supporting the stirrup, and the free end of the bar is held normally in locked engagement with the end of the second mentioned arm of 90 the stirrup.

Pivoted between the ears 14 on the side of the stirrup is a curved lever 21 which extends in an inclined direction, as shown, below the loop B of the stirrup strap and secured to the free end of this lever is a spring 22 which engages against the loop B for the purpose of normally holding the lever 21 in a certain position. The other end of this lever 21 is pivotally connected, 95 as shown at 23, with the upper end of the locking pin 24 which is normally engaged through the slot 16 and through the holes 15 and 20.

In order to attach the stirrup to the strap, 105 the bar 17, being free, is inserted through the loop B, after which the other end of the bar is swung downwardly so that the recess

19 therein will engage over the ear 12. The pin 24 is always within the slot 16 and in order to lock the free end of the bar 17 the lever 21 is swung downwardly which will 5 of course result in projecting the pin 24 through the holes 15 and 20. The parts will then be disposed as shown in Figures 1 and 3 and the stirrup will be firmly supported from the strap.

10 In the event that the rider should slip from his saddle, it is apparent that the toe of his foot will swing upwardly and will engage against the lever 21, moving it toward the loop B against the opposition of 15 the spring 22. When this action occurs, the upper end of the lever 21 will swing outwardly away from the stirrup and will pull the pin 24 out of the holes 15 and 20 and this will of course release the bar 17 so that 20 the latter may swing upon its hinged connection and slip out of the loop B, thus releasing the connection of the stirrup with the strap. It is to be noted that the stirrup will remain upon the foot or boot of the 25 rider but may be very readily subsequently removed.

From the foregoing description and a study of the drawings, it will be apparent that I have thus provided a simple and yet 30 highly efficient means for connecting a stirrup with a stirrup strap in such a way as to permit automatic release of the stirrup from the strap in the event that a rider should fall, the device being consequently a great 35 safeguard against serious injury, such as dragging along the ground in the event of such an accident.

While I have shown and described the preferred embodiment of the invention, it is 40 of course to be readily understood that I reserve the right to make such changes in

the form, construction and arrangement of the parts as will not depart from the scope of the sub-joined claims.

Having thus described my invention, I 45 claim:

1. In combination with a stirrup strap formed with a loop, a U-shaped stirrup, a bar hinged upon the upper end of one arm thereof and having its free end formed with 50 a recess and a hole leading there into, the upper end of the other arm of the stirrup being bifurcated to define inner and outer ears formed with registering openings, said bar normally passing through said loop and 55 having its free end fitting within said bifurcation with said recess receiving the inner ear, and with the hole in the bar registering with said openings, a lever pivoted upon said second mentioned arm of the stirrup and extending below said loop, a leaf 60 spring secured upon the free end of said lever and engaging against said loop, and a locking pin pivotally connected with the 65 other end of said lever and slidably engaged through said hole and said registering openings.

2. In combination with a stirrup strap formed with a loop, a U-shaped stirrup, a bar pivoted upon the end of one arm of the 70 stirrup and normally passing through said loop, a locking pin slidable through the other arm of the stirrup and normally engaging the free end of said bar whereby to prevent movement thereof, a trip lever pivoted upon the second mentioned arm of the 75 stirrup and connected with said locking pin, and a spring carried by said trip lever and engaging said loop.

In testimony whereof I hereunto affix my 80 signature.

PAUL N. WINKLEY.
